TOY AIRPLANE

Jack M. King, Huntington Beach, and George E. Robson,
Torrance, Calif., William D. Stout, Provo, Utah, and
Norman C. Thompson, Bonita, Calif., assignors to
Mattel, Inc., Hawthorne, Calif., a corporation of
Delaware

Filed Nov. 13, 1969, Ser. No. 20,064

Term of patent 14 years

Int. Cl. D21—02

U.S. Cl. D34—15

FIG. 1

FIG. 5

FIG. 2

FIG. 3

FIG. 4

FIG. 1 is a front perspective view of a toy airplane showing our new design;

FIG. 2 is a left side elevational view thereof, the right side is substantially the same as the left side shown;

FIG. 3 is a back view thereof;

FIG. 4 is a front view thereof; and

FIG. 5 is a bottom plan view thereof.

We claim:

The ornamental design for a toy airplane, as shown and described.
